(57) **CLAIM**

The ornamental design for a computing device with media selector user interface, as shown and described.

DESCRIPTION

FIG. 1 is a front perspective view of a computing device with media selector user interface and can be the first image in an animated series; and,

FIG. 2 is a front perspective view of the computing device with media selector user interface and can be the second image in an animated series.

The broken lines showing of various regions and the unshaded areas therein are for the purpose of illustrating the article and form no part of the claimed design.

The appearance of the computing device with media selector user interface sequentially transitions between the images shown in FIGS. 1-2. The process or period in which one image transitions to another forms no part of the claimed design.
